DESIGN.

No. 32,455.

Patented Apr. 3, 1900.

W. H. LANDERS.

STOVE,

(Application filed Jan. 26, 1900.)

UNITED STATES PATENT OFFICE.

WILLIAM H. LANDERS, OF SYRACUSE, NEW YORK.

DESIGN FOR A STOVE.

SPECIFICATION forming part of Design No. 32,455, dated April 3, 1900.

Application filed January 26, 1900. Serial No. 2,916. Term of patent 14 years.

To all whom it may concern:

Be it known that I, WILLIAM H. LANDERS, a citizen of the United States, residing at Syracuse, in the county of Onondaga and State of New York, have invented and produced a new and original Design for a Stove; and I do hereby declare the following to be a full, clear, and exact description of the same, reference being had to the accompanying drawings, forming a part thereof.

Figure 1 represents a perspective view of a stove or furnace, showing my new design. Fig. 2 represents a horizontal sectional view of the same, taken through the lower part of the stove.

As shown in the accompanying drawings, my design consists in the hemispherical main

body A, superimposed upon the rectangular base B, the lateral walls of said base B being provided with vertical recesses b b, substantially semicircular in cross-section, extending up to the hemispherical body A and the pillars C C C C at the four corners of the base B.

What I claim, and desire to secure by Letters Patent, is—

The design for a stove herein shown and described.

In testimony whereof I affix my signature in presence of two witnesses.

WILLIAM H. LANDERS.

Witnesses:

WM. H. HARDING,
B. IVES COOPER.
